UNITED STATES PATENT OFFICE.

THOMAS E. JORDAN, OF MALDEN, AND GERALD J. HENRY, OF MELROSE, MASSACHUSETTS.

DESIGN FOR A SEESAW.

54,267.

Specification for Design.

Patented Dec. 9, 1919.

Application filed July 30, 1919. Serial No. 314,351. Term of patent 7 years.

To all whom it may concern:

Be it known that we, THOMAS E. JORDAN and GERALD J. HENRY, citizens of the United States, and residents of Malden, county of Middlesex, State of Massachusetts, and Melrose, county of Middlesex, State of Massachusetts, respectively, have invented a new, original, and ornamental Design for Seesaws, of which the following is a specification, reference being had to the accompanying drawing, forming part thereof.

In the drawing, Figure 1 is a plan view of a seesaw embodying our new design; Fig. 2 is a side view; Fig. 3 is an end view.

We claim:

The ornamental design for a seesaw, as shown.

THOMAS E. JORDAN.
GERALD J. HENRY.
